UNITED STATES PATENT OFFICE

CONSTANT T. GUNDALL, OF PAWCATUCK, CONNECTICUT, ASSIGNOR TO C. B. COTTRELL & SONS COMPANY, OF WESTERLY, RHODE ISLAND, A CORPORATION OF DELAWARE

SIGNATURE FOLDING MACHINE

Application filed June 10, 1931. Serial No. 543,267.

In signature folding machines where the signatures are first folded transversely and then folded longitudinally, it has been difficult where the longitudinal fold is imparted 5 by the coaction of a folding blade with a pair of folding rolls, to cause the transversely folded signatures to enter the folding rolls square so as to produce a perfect fold. In practice it has been found that the unfolded tail margins of the signatures would fall through the longitudinally disposed slot in the folding table into the pair of folding rolls ahead of the folded heads of the signatures, thereby producing biased folds.

15 I have found that this effect can be remedied by the provision of a more or less flaring slot in the folding table so that both the folded heads and the unfolded tail margins of the signatures will be brought into engagement 20 with the folding rolls at the same moment, thus ensuring perfect square longitudinal folds for the signatures.

One object, therefore, of my invention is to provide means whereby the size and shape 25 of the folding slot may be changed. This means, in the present instance, comprises two longitudinally disposed plates and independent adjusting devices for the ends of said plates so that the adjacent edges of the plates 30 may be positioned either in parallelism or at an angle to each other over the usual rectangular slot in the folding table, to obtain the desired result.

Another object of my invention is to provide the folding rolls with coacting longitudinal knurled portions for engaging the back margins of the signatures, coacting circumferential knurled portions for engaging the 40 tail margins of the signatures and coacting circumferential knurled portions for engaging the closed head margins of the signatures a short distance inwardly from the fold whereby the head folds will not be pinched 45 by the said folding rolls and more even back folds are produced.

A practical embodiment of my invention is represented in the accompanying drawings in which:

50 Fig. 1 represents in side elevation so much

of a signature folding machine as will give a clear understanding of my invention;

Fig. 2 represents a detail end view of the same;

Fig. 3 represents a detail horizontal section taken in the plane of the line III—III of Fig. 1, looking in the direction of the arrows;

Fig. 4 represents a vertical transverse section taken in the plane of the line IV—IV of Fig. 3, looking in the direction of the arrows;

Fig. 5 represents a similar transverse section taken in the plane of the line V—V of Fig. 3, looking in the direction of the arrows.

Fig. 6 represents a similar detail section taken in the plane of the line VI—VI of Fig. 3, looking in the direction of the arrows; and

Fig. 7 represents a detail plan view of the 70 pair of coacting folding rolls to more clearly illustrate the longitudinal and circumferential knurled portions of said rolls.

In the form herein illustrated the transverse folds are formed in the signatures by 75 the coaction of the folding cylinders 1 and 2. The longitudinal folds are imparted to the transversely folded signatures by the coaction of the folding blade 3 with the pair of folding rolls 4, 5. The folding table which receives the transversely folded signatures from the folding cylinder 2 is denoted by 6 and it is provided with the usual longitudinally disposed rectangular slot 7. A pair of longitudinally disposed folding plates 8, 9 are mounted on the folding table 6 over the slot 7 in position to be independently laterally adjusted to change the size and shape of the opening through which the transversely folded signatures are tucked by the folding 80 blade 3 into the pair of folding rolls 4, 5.

Four similar adjusting devices carried by the folding table are provided for independently adjusting the ends of the folding plates 8, 9, laterally.

The devices for adjusting the outer ends of the folding plates comprise laterally disposed aligned adjusting screws 10, 11 having their unthreaded inner ends rotatably mounted in a block 12 secured to the under side of 100

the folding table and their unthreaded outer ends rotatably mounted in their respective brackets 13, 14, depending from the said folding table. The threaded intermediate portions 15, 16 of the screws engage their respective pins 17, 18, depending from the outer ends of the folding plates, through transversely elongated slots 19, 20 in said plate.

10 The devices for adjusting the inner ends of the folding plates comprise laterally disposed adjusting screws 21, 22 having their unthreaded portions rotatably mounted in their respective brackets 23, 24 depending from the folding table. The threaded inner portions 15 25, 26 of said screws engage their respective pins 27, 28 depending from the under faces of the folding plates through the transversely elongated slots 29, 30.

10 A drive shaft 31 is shown as driving the 20 coacting folding rolls 1, 2 through gears 32, 33, 34.

Two sets of coacting feed rollers 35, 36 and 37, 38 are shown for feeding the transversely folded signatures into position on 25 the folding table against the sheet stop 39 which bridges the outer ends of the folding plates 8 and 9. These feed rollers may be driven from the folding cylinder gear 34 through the gears 40 to 45 inclusive. The 30 coacting folding rolls 4, 5 may be driven from the drive shaft 31 through the bevel gears 46, 47, shaft 48 and gears 49 to 54 inclusive.

The folding blade 3 is mounted on a rocking support 55 whose shaft 56 is mounted in 35 suitable brackets 57 carried by the folding table. The support 55 is rocked to raise and lower the folding blade 3 at the proper intervals through a link 58 connected to the crank arm 59 of a shaft 60, which shaft is 40 driven from the gear 52 through the gears 61, 62.

The folding rolls 4 and 5 are provided with coacting longitudinally disposed knurled portions 63, 64 for engaging the back 45 margins of the signatures. These rolls are also provided with circumferential knurled portions 65, 66 for engaging the tail margins of the signatures and with coacting circumferential knurled portions 67, 68 for engaging 50 the closed head margins of the signatures a short distance inwardly from the fold. The ends of the folding rolls beyond the last named knurled portions are of lesser diameters to permit the free passage of the head 55 fold of the signature.

From the above description it will be seen 60 that the two folding plates may be independently laterally adjusted at both their inner and outer ends to obtain the desired shape and size of the folding slot between them, thereby causing the proper insertion 65 of the transversely folded signature into the folding rolls by the folding blade to ensure a perfectly square and unbiased longitudinal fold. In practice I have found that the slot

should be more or less flaring in the direction of travel of the transversely folded signature, according to the signature being folded.

It will also be seen that by circumferentially knurling the outer end portions of the rolls 70 a short distance inwardly from their ends and from the stop 39, the pinching of the transverse fold of the signature is avoided and a better back fold is obtained.

It is evident that various changes may be 75 resorted to in the construction, form and arrangement of the several parts without departing from the spirit and scope of my invention, and hence I do not intend to be limited to the particular embodiment herein 80 shown and described, but

What I claim is:

1. In a signature folding machine, a table having a folding slot therethrough, and means for changing the size and shape of said 85 slot comprising two plates located in the same plane, one of said plates being adjustable with respect to the other in said plane.

2. In a signature folding machine, a table having a folding slot therethrough, and means for changing the size and shape of said 90 slot comprising two plates located in the same plane and adjustable with respect to each other in said plane.

3. In a signature folding machine, a table 95 having a folding slot therethrough, and means for changing the size and shape of said slot comprising two longitudinally disposed plates located in the same plane, one of said plates being adjustable laterally with respect 100 to the other in said plane.

4. In a signature folding machine, a table having a folding slot therethrough, and means for changing the size and shape of said 105 slot comprising two longitudinally disposed plates located in the same plane and adjustable laterally with respect to each other in said plane.

5. In a signature folding machine, a table 110 having a folding slot therethrough, and means for changing the size and shape of said slot comprising two longitudinally disposed plates located in the same plane and independently adjustable laterally with respect 115 to each other in said plane.

6. In a signature folding machine, a table having a folding slot therethrough, two longitudinally disposed plates located in the same plane partially closing said slot, and means for adjusting them in said plane to 120 change the size and shape of the slot.

7. In a signature folding machine, a table having a folding slot therethrough, two longitudinally disposed plates located in the same plane partially closing said slot, and means for independently adjusting them in 125 said plane, to change the size and shape of the slot.

8. In a signature folding machine, a table having a folding slot therethrough, two 130

longitudinally disposed plates partially closing said slot, and means for independently adjusting the opposite ends of each plate to change the size and shape of the slot.

5 9. In a signature folding machine, a table having a folding slot therethrough, two longitudinally disposed plates partially closing said slot, and an individually adjustable device for each end of each plate for changing the size and shape of the slot.

10 10. In a signature folding machine, a pair of folding rolls having circumferentially knurled portions for engaging the head margin only of the signature a short distance inwardly from the head fold.

15 11. In a signature folding machine, a pair of folding rolls having circumferentially knurled portions for engaging the head margin only of the signature a short distance inwardly from the head fold, the ends of the folding rolls beyond the knurled portions being of lesser diameters to permit the free passage of the head fold of the signature.

20 12. In a signature folding machine, a pair of folding rolls having longitudinally knurled portions for engaging the back margin of the signature, circumferentially knurled portions for engaging the tail margin of the signature and circumferentially knurled portions for engaging the head margin of the signature a short distance inwardly from the head fold.

25 13. In a signature folding machine, a pair of folding rolls having longitudinally knurled portions for engaging the back margin of the signature, circumferentially knurled portions for engaging the tail margin of the signature and circumferentially knurled portions for engaging the head margin of the signature a short distance inwardly from the head fold, the ends of the folding rolls beyond the last named knurled portions being of lesser diameters to permit the free passage of the head fold of the signature.

30 40 45 14. In testimony, that I claim the foregoing as my invention, I have signed my name this eighth day of June, 1931.

CONSTANT T. CUNDALL.
